UNITED STATES PATENT OFFICE

ALEXANDER WINTON, OF LAKewood, OHIO

INJECTION NOZZLE

Application filed April 16, 1928. Serial No. 270,491.

This invention relates to fuel injection nozzles for hydrocarbon motors of the solid fuel injection type.

Particularly in small sizes of such engines, 5 the mechanical problems involved in forming nozzle injection openings of suitably small size and accuracy are very considerable.

An object of my invention is a nozzle design wherein the injection opening area there- 10 of may be as small as desired and yet very accurately and comparatively easily produced.

More specifically, instead of attempting to provide the usual minute cylindrical opening 15 as by means of a jeweler's drill or needle, I provide a relatively larger opening as with a drill of sufficient size that the opening may be accurately made; and reduce the effective opening to provide the desired passage area 20 by inserting therein a rod which may be easily and accurately made, and properly calibrated to give the proper net injection passage area.

Thus that portion of the rod member positioned in the opening of said nozzle may very 25 nearly occupy the nozzle opening in transverse dimension, yet have a minute clearance therefrom, the clearance providing a passage-way defined by said parts and of endless 30 linear sectional characteristic, that is, in section the effective passage will be an endless line the transverse dimension of which may by proper proportioning of the parts, be made to approach zero substantially as closely 35 ly as desired.

The exact nature of my invention together 40 with further objects and improvements therein will be apparent from the following description taken in connection with the accompanying drawings in which Fig. 1 is a 45 sectional view through an injection nozzle and its immediately adjacent parts constructed according to my invention, the drawing being drawn to a scale much larger than the minimum size to which I have been able to work; Fig. 2 is a detail still further enlarged over the showing of Fig. 1, of the combustion chamber end of the same nozzle; and Fig. 3 50 is a section as in the plane of line 3-3, Fig. 1, but correspondingly enlarged.

With reference now to the drawings, 1 is a portion of the cylinder wall of a hydrocarbon motor designed for operation on a solid fuel injection cycle and having a through opening to fit a cylindrical plug member 2. 55 The member 2 has a head portion 3, a taper portion 4 fitting a taper in the cylinder wall, threads 5 fitting threads in the cylinder wall opening and a nozzle portion 6 closely fitting the opening in the cylinder wall and terminating in a face 7 lying generally in the plane of the face 8 of the cylinder wall which forms one of the confines of the combustion chamber of the engine. The member 2 is bored, counter-bored and internally threaded as indicated, the head end of the member being adapted to have connection as by means of the bolt 9, with a fuel supply pipe 10.

The member 2 has for a greater part of its extremity a central bore 11 of relatively 70 large diameter but at its nozzle end is necked down as at 12 and provided with a smaller opening 13 very accurately drilled out to the proper diameter. The proportions are preferably such that the longitudinal dimension 75 of the neck 12 is approximately that of the diameter of the bore 13, since increasing this dimension unduly increases tendency to clog and difficulties of alignment, and decreasing this dimension makes the structure unduly 80 subject to wear.

The member 2 has midway of its length threads 14, and fitting therewithin a plug 15 having a transverse slot 16 at its head end, an axial opening 17, and longitudinally extending milled slots 18 spaced about its periphery.

A rod 19 is provided as indicated having a short bend 20 at its head end fitting the slot of the plug 15 and extending through the opening 13 of the nozzle. The rod 19 may 90 be simply a piece of steel wire but at least that portion thereof extending through the opening 13 is quite cylindrical and very accurate as to dimension.

For a given diameter of opening 13, therefore, by providing the proper diameter of rod inserted in the opening, a cylindrical annular nozzle passage of very accurately determined passage area is produced, and it will be apparent that the passage will be defined by 95 100

- the relation of the parts rather than by their absolute dimensions and may, therefore, be of endless linear sectional characteristic as described above. The rod may be loose in the plug 15 as well as in the opening 13, and the plug and rod are retained in the nozzle by the usual head 21 secured on the end of the tube 10 and prevented from withdrawal by the nut 9.
- 10 Operation will be as follows. Fuel entering the nozzle by way of the tube 10 may flow past the plug 15 by way of the grooves 18, thence along the annular passage between the rod 19 and the bore 11 and to the opening 13.
- 15 Upon the proper injection pressure this fuel will be violently injected into the combustion chamber by way of the annular passage within the neck 12, the rod end automatically assuming under such conditions a central position in the opening 13.

20 As has already been stated, by the means described a very minute injection passage may be formed quite accurately, and as will be well understood by one familiar with the art great accuracy of dimension at this point is necessary for efficient results.

25 What I claim is:

Fuel injection means of the class described, comprising a plug member adapted for insertion in the combustion chamber wall of a hydrocarbon motor and having a through opening terminating in a nozzle portion, a plug fitting in said opening and having a longitudinal slot, a central opening and a transverse slot, and a rod member having a portion extending through said plug opening and into said transverse slot, and having a portion extending into said nozzle portion, whereby a passage opening is defined by the clearance between said nozzle portion and the rod portion therewithin, said rod is maintained against rotation by engagement with said transverse slot, and passageway is had along said longitudinal slot.

30 45 In testimony whereof I hereby affix my signature.

ALEXANDER WINTON.
